VISIBLE RECORD SYSTEM

Marchand B. Hall, Chicago, Ill., assignor to Acme
Visible Records, Inc., Chicago, Ill., a corpora-
tion of Delaware

Application February 26, 1940, Serial No. 320,824

12 Claims. (Cl. 129—16)

This invention relates to improvements in visible record systems, and particularly to the type wherein means are provided whereby one or a plurality of record cards, mounted upon hangers, and disposed in spaced overlapping relationship upon a suitable support or tray, may be displaced or offset laterally either to the right or left with respect to the neutral or normal position of the remaining cards upon the tray or support, and may be positively maintained in normal position or in displaced position in either direction.

Lateral displacement and positioning means in combination with visible record systems as herein contemplated find use as either temporary, permanent or periodically variable identification, classification, follow-up, or like signalling aids, as for example, in the classification of postings, credit ratings, payment or collection follow-ups, purchase and order reminders, and the like. A device adapted for like use is set forth in United States Patent No. 1,993,510 to Edward C. Gast, Jr.

The lateral offset and positioning means of the present invention is adapted for use in combination with conventional visible index frames or supports utilized as trays or drawers of record cabinets, leafs of record books, units of the usual swingably mounted record or index stands, and the like, without modification thereof. Likewise the card hanger means, as hereinafter more fully described, are interchangeable with conventional card hangers not provided with lateral card displacement means, and if desired, a single frame or tray may contain both classes of card hangers at one time.

As a further feature of this invention, the card hangers are adapted to be mounted in fixed position on the tray or holder and retained by the conventional flanges thereof, so that no friction impediment is set up between the lateral displacement means of adjacent supported cards, tendencies of the hangers to buckle, shift, collapse or to become displaced in the holder are prevented and eliminated, and as a result freedom of lateral movement and positioning of the cards without interference from or contact with adjacent hangers is maintained at all times, and a more perfect operative means provided than has heretofore been known in similar devices.

Various other objects and advantages of my invention relating to the utility thereof, its economies, and arrangement of parts will be apparent from a consideration of the following specification and drawing, wherein:

Fig. 1 is a front elevational view illustrating a fragmentary portion of a record or index unit embodying my improved offset hanger device.

Fig. 2 is a sectional view taken on the line 5—2 of Fig. 1.

Fig. 3 is a fragmentary detail view of the offset positioning member of my device.

Fig. 4 is a perspective view of the two interengaged portions of my offset hanger device.

Fig. 5 is a fragmentary detailed sectional view taken on the line 5—5 of Fig. 1.

In general my improved offset hanger device comprises two members, one of which is substantially in the form of a conventional card hanger well known in the art comprising a flexible wire formed with return-bent end portions adapted for insertion by flexing or springing beneath the flanges or the tray or holder, the return-bent portion terminating in offset ends adapted to engage hinges attached to record cards. These hangers are modified by a double offset intermediate their length and thereby adapted to interengage and become operatively associated with the second or positioning member. This second member may likewise be in the form of a wire or flat flexible metal strip having upstanding end ear portions slidably positioned on the terminal ends of the hanger and of a length to straddle the card hinges. The positioning member is formed intermediate its length with a plurality of crimps adapted to yieldably engage the intermediate offset of the hanger and whereby lateral shifting of a mounted card will cause lateral movement of the positioning member to engage one of its crimps with the intermediate hanger offset and fix the record card in one of a predetermined number of positions, all without shifting or movement of the hanger portion in its mount.

Referring to the drawing, 10 indicates a conventional card holder frame provided with channels 11 for receiving the wire hangers 12. The hangers 12 are formed with return-bent ends 13 and as indicated, are generally provided with parallel offset terminals 14 for receiving hinges 15 engaged to record cards 16 in the conventional manner. However, as modified in accordance with this invention, the hangers 12 are formed intermediate their length with a double offset to form a substantially U-shaped portion 17 comprising legs 18 and 19, the whole lying substantially in the same plane formed by the return bends 13 with the body 12 of the hanger. Thus when the hanger 12 is sprung or flexed and positioned within the channels 11, the U-portion

17 lies substantially in the plane of the holder 10.

The card offset member, generally designated as 20 may be formed of wire similar to hanger 12, or preferably of a flat flexible metal strip as shown, the opposed ends terminating in the up-standing perforated ears 21, which it is understood may be in the form of loops if the portion 20 is formed of wire. Intermediate its length the card offsetting member 20 is formed with a plurality of positioning crimps extending upwardly at an angle from the face of the plane determined by the hanger return bend portions 13, the drawing illustrating three crimps 22, 23, and 24 for positioning an engaged card 16, in left-offset, neutral and right-offset positions respectively, although it will be evident that additional positions by means of like additional crimps may be provided.

In operatively associating the hanger member 12 and offsetting member 20, they are interengaged or entwined, that is, the member 20 is first engaged by an ear 21 to a hanger terminal 14 with the recesses of the crimps 22, 23, 24, opening downwardly and overlying the leg 18, the strip 20 being thereafter caused to underlie the leg 19 after which the second ear 21 is engaged to the second hanger terminal 14. In this position the offsetting member 20 may be moved laterally and the crimps 22, 23, 24, caused to yieldably engage the leg 18, the intermediate crimp 23, being formed at a point whereat engagement thereof will cause a card 16 to be set in neutral position and engagement of crimps 22 and 24 will set the card in left offset and right offset positions respectively. It will be evident that due to the intertwined engagement of members 12 and 20, the base of the double offset or U will prevent disengagement of the members in one direction, and to prevent disengagement in the opposed direction, an additional crimp 25 is provided spaced apart from crimp 24 a sufficient distance to permit cooperation of all of the crimps 22, 23, 24, with leg 18, and outwardly of U bend. The length of the offsetting member 20 and correspondingly the free lengths of the hanger ends 14, is such as to permit sliding engagement for a distance at least equal to that from the intermediate crimp 23 to either crimp 22 or crimp 24, or greater if there are more crimps for additional positions and the length of the base of the double offset or U 17 is substantially equivalent to the length of that portion of strip 20 comprehended by all of the positioning crimps. The hinges 15 are engaged to cards 16 in pairs spaced apart so that they are straddled or embraced in abutting engagement by the ears 21 of the offsetting member 20.

The operative intertwining engagement of the members 12 and 20 provides a spring tension on the positioning crimps 22, 23, 24 effecting the ease of operation, rigidity of positioning and prevention of accidental or unintentional displacement, and which is substantially independent of the length of hanger member 12. It will be noted, particularly from Fig. 3, that member 20 is offset between adjacent crimps 22, 23, 24 and 25, and by this means the aforesaid tension may be regulated by increasing or decreasing the elevation or degree of this offset. Likewise the tension on the positioning crimps may be varied by increasing or decreasing, within operative limits, the length of the base 17 or the spacing of the legs 18 and 19 of the U formation on the hanger member 12.

Thus in operation it is merely necessary to interengage the members 12 and 20 as hereinbefore

described and position the hanger in the tray or holder by the conventional springing or flexing action, after which it remains positioned in the frame in fixed position. A record card provided with hinges in properly spaced apart engagement is then placed on the hanger ends 14 so as to have the hinges in abutment with the ears 21. Thereafter it is only necessary to grasp the card and move it laterally which causes the hinges to ride on the ends 14 and the offset member 20 to move with it and the crimps 22, 23, 24 into and out of engagement with the leg 18, and by reason of the flexibility of the member 20 and its interengagement with member 12, positioning and repositioning of the record card may be carried out positively and with ease, and at the same time tendency toward accidental or unintentional displacement of the positioned cards or hangers is substantially eliminated.

20 I claim as my invention:

1. In a visible card system, the combination with a frame having guide channels of detachable flexible wire hangers fixedly positioned therein against movement laterally of the frame, cards mounted by hinge means on said hangers and movable laterally to an offset position, and an offsetting member operatively associated with and slidably mounted on each of the said hangers in straddling engagement with the hinges of the mounted card.

2. In a visible card system, the combination with a frame having guide channels of detachable flexible wire hangers fixedly positioned therein against movement laterally of the frame, cards mounted by hinge means on said hangers and movable laterally to an offset position, and an offsetting member operatively associated with and slidably mounted on each of the said hangers in straddling engagement with the hinges of the mounted card, the said offsetting members each comprising a flexible strip formed intermediate its length with means adapted for yieldable variable engagement with engageable means formed on a corresponding one of said hangers.

3. In a visible card system, the combination with a frame having guide channels of detachable flexible wire hangers fixedly positioned therein against movement laterally of the frame, cards mounted by hinge means on said hangers and movable laterally to an offset position, and an offsetting member operatively associated with and slidably mounted on each of the said hangers in straddling engagement with the hinges of the mounted card, the said cards and associated offsetting members being laterally displaceable with respect to said hangers and said frame, and copreable means formed on each hanger and each offsetting member for retaining the offsetting member and embraced card in normal or displaced position.

4. In a visible card system, the combination with a frame having guide channels of detachable flexible wire hangers fixedly positioned therein against movement laterally of the frame, cards mounted by hinge means on return bent end portions of said hangers and movable laterally thereon to offset position, and a flexible offset positioning member carried by each of said hangers on said ends thereof and movable longitudinally with respect thereto and in straddling engagement with a pair of card hinges, the said offsetting member being formed with a plurality of crimps intermediate the length thereof and operatively associated with a hanger by being extended through a U bend formed on

said hanger intermediate its length, the said U bend lying substantially in a plane formed by said return bent hanger end portions, the said crimps being in overlying engagement with one of the legs of said U bend and yieldably engageable therewith to retain said offsetting member and embraced card in desired lateral position on said frame.

5. In a visible card system, the combination with a frame having guide channels of detachable flexible wire hangers fixedly positioned therein against movement laterally of the frame, cards mounted by hinge means on return bent end portions of said hangers and movable laterally thereon to offset position, and a flexible offset positioning member carried by each of said hangers on said ends thereof and movable longitudinally with respect thereto and in straddling engagement with a pair of card hinges, the said offsetting member being formed with a plurality of positioning crimps intermediate the length thereof and said hanger being formed with a double offset intermediate its length, the said offsetting member lying over one of said offsets and under the other, the said crimps being engageable with the former offset to retain said offsetting member and embraced hinge mounted card in normal or desired laterally displaced position.

6. In a visible card system, the combination with a frame having guide channels of detachable flexible wire hangers fixedly positioned therein against movement laterally of the frame, cards mounted by hinge means on return bent end portions of said hangers and movable laterally thereon to offset position, and a flexible offset positioning member carried by each of said hangers on said ends thereof and movable longitudinally with respect thereto and in straddling engagement with a pair of card hinges, the said offsetting member being formed with a plurality of positioning crimps intermediate the length thereof and said hanger being formed with a double offset intermediate its length, the said offsetting member lying over one of said offsets and under the other, the said crimps being engageable with the former offset to retain said offsetting member and embraced hinge mounted card in normal or desired laterally displaced position, the said offsetting member being formed with a locking crimp spaced from said positioning crimps for maintaining said members in operatively associated position.

7. An offset mounting device of the class described comprising a flexible wire hanger member adapted to be detachably mounted and fixedly positioned on a holder frame therefor against movement laterally of the frame, and a flexible offsetting strip member operatively associated therewith and movable longitudinally thereof, the said offsetting member being formed with upstanding ends and adapted to straddle opposed hinges of hinge mounted record cards and being movable with respect to said hanger by manual lateral movement of said cards, the said offsetting member being formed intermediate its length with means yieldably associable with engageable means formed on said hanger.

8. An offset mounting device of the class described comprising a flexible wire hanger member adapted to be detachably mounted and fixedly positioned on a holder frame therefor against movement laterally of the frame, and a flexible offsetting strip member operatively associated

therewith and movable longitudinally thereof, the said offsetting member being formed with upstanding ends and adapted to straddle opposed hinges of hinge mounted record cards and being movable with respect to said hanger by manual lateral movement of said cards, the said offsetting member being formed intermediate its length with a plurality of crimps yieldably engageable with an offset formed on said hanger member to retain said offsetting member in desired longitudinal relationship with said hanger member.

5 9. An offset mounting device of the class described comprising a flexible wire hanger member adapted to be detachably mounted and fixedly positioned on a holder frame therefor against movement laterally of the frame, and a flexible offsetting strip member operatively associated therewith and movable longitudinally thereof, the said offsetting member being formed with upstanding ends and adapted to straddle opposed hinges of hinge mounted record cards and being movable with respect to said hanger by manual lateral movement of said cards, the said offsetting member being formed intermediate its length with a plurality of crimps yieldably engageable with an offset formed on said hanger member to retain said offsetting member in desired longitudinal relationship with said hanger member.
